INVENTOR:
W. Ryan Jr.

UNITED STATES PATENT OFFICE

1,974,726

REFRIGERATOR TRUCK COOLING APPARATUS

William Ryan, Jr., University City, Mo.

Application August 17, 1933, Serial No. 685,569

1 Claim. (Cl. 62—117)

This invention relates to the manner of mounting a compressor and a condenser, associated with a refrigerating system, on a vehicle, and especially with the manner of driving said compressor.

Mechanical refrigeration in vehicles of this kind are common, but heretofore, as far as I am aware, the compressor used in such systems is driven by a separate engine located at any suitable place on the body of the vehicle.

10 The principal object of this invention is to obviate the necessity of such extra engine, and contemplates driving the compressor directly from the crankshaft of the engine which propels the vehicle itself.

15 Another object of this invention is to so mount the compressor that the refrigerating system can readily be operated if necessary, from an outside source of power, and that slack in the driving belts may be taken up without the use of a belt 70 tightener or similar device.

A further object is to accomplish these results without the necessity of in any way changing the design of the engine or other parts of such vehicle as now built by the manufacturer.

25 The mounting of the condenser in front of the radiator where the cooling blast from the fan, as well as the onrushing air as the vehicle moves forward both strike said condenser, is also considered a feature of the invention. It is, of course, understood that ordinarily, deliveries of perishable commodities take place at night or in the very early morning when the air is cool.

Naturally, it is then that the system operates at its best. I have found, however, by actual test, 35 that a refrigerating system installed on a truck as hereinafter described, operates efficiently also in higher temperature later in the day.

Other features inherent in this invention will be apparent from a detailed description of the 40 same hereinafter.

In the accompanying drawings which form part of this specification, and in which like reference characters refer to like parts wherever they occur, Fig. 1 is a plan view of a motor propelled 45 vehicle embodying my invention; Fig. 2 is a side elevation thereof; Fig. 3 is a vertical section on the line 3—3 of Fig. 2, illustrating the manner of mounting the condenser; Fig. 4 is a side elevation of Fig. 3; Fig. 5 is a fragmentary front elevation 50 of an engine, a compressor, and mounting and driving means thereof; Fig. 6 is a side elevation of Fig. 5; Fig. 7 is a plan view of the plate upon which the compressor is mounted; Fig. 8 is a vertical sectional view of a sheave to be fixed on the 55 crankshaft of the engine, after the removal of

the customary sheave for driving the fan with which the crankshaft is equipped.

Referring now more particularly to Figs. 1 and 2 there is shown at numeral 1 a truck provided with a cold storage compartment 2, in which is mounted a plurality of cooling units, and to which access may be had by a door or doors. In the present instance two such cooling units 3, and 3a are shown, although it is obvious that any number of such units may be employed. At 4 is shown 60 conventionally a compressor. Numeral 5 indicates a condenser which is positioned immediately in front of the radiator in a manner to be described in detail. A receiving tank 6 is fastened to the chassis in any suitable manner, and a line 65 7 leads from the compressor to the condenser. Another line 8 leads from the lower portion of the condenser to the receiving tank 6, line 9 leading from said receiving tank to the cooling coil 3. A branch line 10 leads to the other cooling unit 3a. 70 A line 11 leads from cooling unit 3 to the compressor 4, branch line 12 from cooling unit 3a also leading into 11. The arrows in Fig. 1 indicate the flow of the refrigerant.

It is, of course, understood that this circuit of 80 coils and pipes constituting the refrigerating system, is shown diagrammatically and may be varied to meet conditions. Valves, etc., in the circuit are not indicated, since this invention does not concern itself with any components of the 85 system except the compressor and condenser.

The engine of the vehicle is conventionally shown at 13, see Figs. 5 and 6. An angular bracket 14 is so formed as to be capable of being mounted directly upon the engine without changing any of the existing parts. As shown in Figs. 5, 6 and 7 a downwardly extending vertical portion 16 of the mounting plate 14 is bolted rigidly to the generator housing 15, as by cap screws 18 which pass through holes in the semi-annular bifurcated extremity 17 of said vertical portion, and into the generator housing. The holes in said bifurcated portion of the mounting plate are in alignment with the sockets found in the generator housing so that it is merely necessary to obtain cap screws 95 of a sufficient length to compensate for the thickness of the bracket to secure it in place.

The horizontal portion 19 of the mounting plate 14 is provided with four slots 20 which will permit horizontal, that is, lateral adjustment of the 105 compressor to and away from the engine when found necessary. The base of the compressor 21 rests on said horizontal portion 19, and carries four bolts 22 which pass through the slots 20, and are provided with locking nuts whereby the com- 110

pressor is held in place. The position of the compressor is, of course, determined by the length of the belts used, and the adjustment possible by means of the slots 20 and bolts 22 obviate the necessity of a belt tightener.

In order more rigidly to support the compressor, brackets 23 and 24 are bolted to the engine block and likewise to the underside of plate 19. Numeral 25 indicates the sheave of the compressor fixed on the compressor drive shaft 26. Numeral 27 indicates a belt. While it is not necessary to use more than one belt 27, I have found it more practical to use two such belts.

In this connection, I have discovered by numerous tests, that in mounting the compressor as outlined above, I have overcome the most serious handicaps emanating from vibration. The vibrations of a motor such as employed in vehicles of the type herein referred to, are frequently such as would hamper the efficient operation of a compressor mounted directly upon said motor. In addition the inlet and outlet connections of said compressor would be subjected to constant jarring, apt to cause loose connections and leaks. As noted above, I mount the principal compressor supporting plate on the housing of the generator, which although integral with the motor also tends to vibrate independently. The compressor itself vibrates independently also. By the use of the plate and brackets referred to, these three vibrating units are so inter-connected as to minimize or stabilize all of the vibrations, averting the disadvantages mentioned.

In connection with the lateral adjustment of the compressor, there may be times when the refrigerating apparatus should be kept in operation while the vehicle is not. At such times it is merely necessary to loosen the bolts 22, slide the compressor 4 towards the engine, remove the drive belt or belts 27 and connect them with another source of power which can easily be brought alongside the truck.

As before stated the customary sheave which is found on the crankshaft is removed, and a triple sheave such as shown in Fig. 8 is keyed to the crankshaft in such manner as not to interfere with the cranking of the engine. I have indicated the sheave by the numeral 28. Two of the grooves in this sheave are engaged by the belts 27; the other groove is engaged by the fan belt 29.

It is, of course, apparent that the hood must be cut away as at 30 to accommodate the compressor.

The condenser 5 shown conventionally, comprises among other elements a rectangular frame 31. Numerals 32 indicate the side frames of the chassis, numerals 33 the fenders. Rectangular openings 34 are cut in the fenders 33 adjacent the side frame members 32, for accommodating the lower right and left hand corners of the condenser frame 31, said corners fitting the openings snugly. Two brackets 35 having oppositely disposed flanges at their ends maintain the condenser frame 31 in a rigid upright position. The upper flange of each bracket 35 is fastened to the frame 31 in any suitable manner, screws being here shown. The oppositely outstanding base flange of each bracket at the lower end is bolted to the side frame 32, as by bolts 36.

The rigidity of the condenser frame when mounted in this manner is apparent. The rectangular frame encasing the condenser unit is made of strong durable metal, affording the coils and associated cooling fins adequate protection. The corners of said frame "fit" the openings in the fenders, this arrangement together with the brackets 35 insuring essential stability of the condenser, preventing loose connections, leaks, etc.

From the foregoing description it will be seen that the various objects of the invention are achieved. The necessity of maintaining a separate source of power, for driving the compressor, with its initial and continuous expense is eliminated, and the condenser is placed in the most advantageous position on the vehicle.

Obviously, numerous changes could be made without departing from the scope of this invention, and I do not wish to be limited to the precise construction illustrated in the drawings.

Having described my invention, I claim:—

In combination with a refrigerator truck having an internal combustion engine, provided with a fan for driving air which cools the engine and a condenser, mounted on said truck, and a crank-shaft driven by said engine, a sheave fixed to said crank-shaft, a plurality of belts mounted on the sheave, one belt to drive said fan, the other belt driving a sheave fixed to the driveshaft of a compressor, which supplies high pressure refrigerant to said condenser.

WM. RYAN, JR. 125
